UNITED STATES PATENT OFFICE.

OTTO P. AMEND, OF NEW YORK, N. Y.

PROCESS FOR CRACKING OR CONVERTING OILS.

Application filed March 3, 1922. Serial No. 540,725.

This invention relates to the art of cracking crude petroleum, heavy naphthas, kerosene, and higher-boiling hydrocarbon distillates or residuals, or combinations of the same, whereby they are transformed or converted into lower-boiling hydrocarbons, suitable for use in internal combustion engines, and for the various other purposes for which low-boiling petroleum distillates are employed. The process is applicable either to hydrocarbons of the paraffin, naphthene, or polymethylene series, or to mixtures of hydrocarbons of the same or different series. The process is especially applicable to any of the higher-boiling petroleum distillates, such as kerosene, Mexican distillates, gas oils, and fuel oils.

The cracking methods heretofore employed commercially involve the external heating of the oils, and the pronounced disadvantages inherent in such heating are so generally recognized in the art that a specific enumeration of such disadvantages is not deemed necessary. It may be stated, however, that said processes are inefficient, in that they are slow in operation and convert only comparatively small percentages of the oils operated upon, and, moreover, are attendant with very considerable danger owing to the deposit or caking of heat insulating carbon on the bottom of the oil treating still or receptacle.

Moreover, the temperature required to properly crack the oils is so relatively high that when externally applied it results in raising the temperature of the walls of the still to such extent that their capacity to withstand the pressure within the still is seriously impaired, and there is great danger of the walls giving way under the pressure produced, so that not infrequently, serious explosions are thus occasioned. For these reasons, among others, great care must be exercised in the carrying out of the processes involving external heating.

The process forming the subject matter of the present invention enables me to secure any desired suitable cracking temperatures, yet the sides and bottom of the still or digester are maintained relatively cool, and, accordingly, the ability of the metal of the containing vessel to resist pressure is not seriously impaired. As a result, much higher pressures may safely be availed of than can be safely used in the processes in-

volving the external heating of oil in large stills. The present process permits of the employment, with safety, of a pressure in large stills in excess of one hundred pounds, whereas such pressures are not practicable, so far as I am aware, in any process involving the heating of the oil externally, and, more particularly, in large stills.

With a view to overcoming the disadvantages adverted to, various expedients have been suggested, such as the employment of electric heating elements positioned within the oil treating chamber, but these heaters have been of such structural character, and they were employed and operated under such conditions, that their use did not produce commercial results, and, so far as applicant has been able to determine from authoritative sources, the electrical expedients referred to have been discarded as impractical.

Referring more specifically to the manner in which the electrical heating elements were employed, attention is called to the facts that they were heated to incandescence, a temperature entirely too high; that the oils or vapor under treatment were maintained at comparatively low pressures, or even under a partial vacuum, conditions highly averse to successful or efficient cracking; and, further, only a very small volume of oil, and that generally in a flowing condition, was operated upon, such as heating the oil while flowing through pipes or tubes, a mode of operation which has been demonstrated to be wholly impractical, because of the facts, mainly, that if an efficient cracking temperature is attained, the small volume of oil operated upon is apt to be over-cracked, i. e., partially gasified, whereas, if a sufficiently high temperature for the rapid cracking is not attained, the flowing small body of oil does not remain sufficiently long in contact with the heating element to be effectively cracked.

The present invention overcomes the disadvantages inherent in the older, though still generally employed, cracking methods referred to, ante, but has successfully solved the problem of cracking oils by utilizing internal heaters, in the form of electric resistors, under such conditions of operation that most unexpected scientific results are obtained, as well as exceptional commercial efficiency, more particularly as regards the rapidity of cracking and the large percent-

age of the oil under treatment which can be cracked, results of such extent and character as were not heretofore considered feasible.

Speaking generally, applicant's process embodies, in its substantial entirety, the following features: the employment of electric resistors, preferably of carbon, submerged in the body of oil under treatment; the heating of the resistors to a temperature which will maintain their exposed or active surface or surfaces at a temperature below incandescence, but sufficiently high to effect efficient cracking without causing undue gasification, this temperature being dependent, of course, on the particular cracking temperature of the specific material operated upon; the treatment of a relatively large body of oil, in a comparatively quiescent condition, in contradistinction to treating, as was heretofore the case when electric heaters were employed, a comparatively small body of oil, usually, as pointed out, in a flowing state or condition; efficient refluxing of the uncracked oil, whereby the total yield of cracked products is greatly enhanced, and the employment of a relatively high pressure, particularly as compared with the pressures suggested in the prior art process wherein it was attempted to use electric heaters. It will be understood, of course, that the invention is not restricted to the employment, conjointly, of all the steps pointed out, since some of the operations, per se, are novel. In practice, I prefer to use an alternating current, though the process is not restricted to such current, and I have found that, with respect to the current, the extent of cracking, assuming an efficient cracking temperature is maintained, is dependent, mainly, on the quantity of electric energy efficiently supplied to the resistors. Good results have been obtained by using resistors in the form of slabs having a cross sectional area of $1\frac{1}{4}$ by $6\frac{1}{4}$ inches, and having a length of 6 feet or more. It will be noted that the resistors employed are heavy or massive, and, accordingly, that the oil is exposed to extended carbon heating surfaces. The resistors accumulate more less carbon, i. e., are built up by the deposit of carbon freed in the cracking process, so that they should be amply spaced apart from each other, and, also, from the walls of the still or treating receptacle in order to avoid short circuiting.

My experience has demonstrated that in the employment of submerged resistors, as practiced in the present process, a comparatively high pressure is essential to effective commercial cracking. This seems to be occasioned by the fact that the resistors, at the temperature employed, appear to have somewhat of a tendency to repel the oil and thus preclude intimate contact between the resistors and the oil. The result is that

without employing a suitably high pressure, considerable of the oil is merely vaporized without being cracked. Accordingly, one of the most important functions of the pressure, in the present process, is to enforce close contact or engagement between the oil and resistors, though, of course, such pressure does incidentally, raise the boiling point of the oil. It is manifest, now that it has been pointed out, that the closer the contact is maintained between the oil and the resistors, the more effective will be the cracking, and vaporization without cracking will be reduced to a minimum.

For the reasons given, I prefer to operate at a minimum pressure of from 75 to 80 lbs., although intermediate pressures from the minimum specified to upwards of 150 lbs. have all given excellent results.

By the employment of the electric resistors as herein described, the temperature of the body of the oil can be regulated and controlled to a nicety, and this nicety of temperature regulation results in much more regular production of a uniform quality of product than is possible in any process dependent on external heating. I prefer to operate at a temperature between about 800° F. and 1100° F.

Features of the process, other than those adverted to, will be apparent from the hereinafter description and claims, read in conjunction with the accompanying drawings.

The drawings illustrate, somewhat diagrammatically, an apparatus forming part of my invention, which can be used in carrying out applicant's process, although it will be understood that such apparatus is illustrative only of one type of apparatus which may be thus employed.

In the accompanying drawings,

Fig. 1 is an elevation, partly in section and partly broken away, of a still embodying the invention and adapted for carrying out the process of the invention, and

Fig. 2 is a fragmentary section on line 2—2 of Fig. 1.

Referring to the drawings, A is a still having an oil inlet a, and a gas inlet b extending nearly to the bottom of the still, the function of which will be hereinafter described. The still is heated by means of a submerged carbon heating element or elements c, hereinafter termed a resistor, in the form of a plate, or tubular as shown, and, the said resistor is provided with suitable terminals d and d', properly insulated from the walls of the still. Moreover, the resistor is spaced a very considerable distance from the walls of the still so as to preclude any likelihood of short circuiting.

Oil, which, if desired, may be preheated, is introduced into the still through the pipe a which is fed either directly from a pipe

a' leading from any suitable source, from a pipe *a²* through which the oil is forced by a pump *a³*, fed from any suitable supply. In the pipe *a²* is included a pre-heated coil *a⁴*, so that, if desired, the oil may be preheated before entering the still A, the advantage of which is manifest. Coil *a⁴* is preferably heated in a manner hereinafter described.

19 When current is passed through the resistor its surface temperature is raised to the desired degree for effective cracking, usually to approximately 800 degrees F., which is considerably below incandescence.

15 Naturally, however, the interior body of the carbon resistor is at a somewhat higher temperature than the temperature of its surface. The volatile products of the cracking process pass off from the still, and 20 enter a reflux tower A' superimposed on the still, whence they enter an outlet pipe B. Tower A' is preferably of such height and size that during the passage of the products of the cracking operation there- 25 through sufficient refluxing action will take place so as to allow the return to the still of uncracked oil vapors carried along by the products of the cracking operation, and through such refluxing action enhance the 30 quality and quantity of the resulting product.

A further refluxing action may be carried on by inclining the outlet pipe B in an upward direction, although, if desired, the pipe 35 B may extend in any desired direction if the tower A' is sufficiently high to properly carry out its functions.

Pipe B leads to a cooling coil D, housed 40 in a casing E, through which a cooling medium, such as water, is circulated through inlet and outlet pipes *e* and *e'*, respectively. During the passage of products of the cracking operation through coil D, the temperature is sufficiently lowered to condense the 45 greater portion thereof, although a small percentage of such products remain in gaseous form. The condensate from coil B, passes through a pipe F, controlled by a valve F', into a receiving tank G. The 50 liquid is retained in tank G, but any gaseous or uncondensed volatile products finds exit through a pipe *h*, provided with a relief valve H', whence it passes into a gas tank II. Tank II, is provided with an outlet pipe *i*, in which is located a manually controlled valve *i'*, whereby the gas may be fed 55 to a burner I, for the purpose, if desired, of preliminarily heating the oil prior to its introduction into the still. The still is provided with means, such as a valved draw-off pipe *k*, whereby separated carbon or oil residues may be removed therefrom. The 60 tank of the reservoir G has a draw-off pipe *g*, controlled by a valve *g²*, through which the condensate may be drawn-off, and fur-

ther treaded if desired. A gage glass *g'* is preferably associated with tank G so that the height of the liquid therein may be observed.

From the foregoing description of the 70 apparatus, and the described functions of the several parts thereof, the manner of carrying out applicant's process will be readily understood, and it may be described, briefly, as follows: As a precaution, it is 75 usually considered advisable to remove air from the apparatus, and this may be done by displacement by causing a flow of suitable gas, such as natural gas, therethrough, which gas is introduced into the still 80 through pipe *b*. Still A is thereupon supplied with oil, either intermittently or continuously, preferably in one of the ways specified, and I have found it advisable to fill the still to about two thirds of its 85 capacity, the resistor *c* being preferably completely submerged therein. Electric current is then supplied to the resistor, whereupon, in a short time, an autogenous pressure is built up in the still, preferably 90 ranging from 75 to 150 pounds, and which may be regulated by means of the pressure valve B' or in any other suitable way. The desired cracking temperature, dependent to some extent, of course, on the most effective 95 cracking temperature of the particular oil under treatment, is constantly maintained, and a relatively large percentage of the cracking proceeds with regularity and expedition, resulting in the production of a 100 uniform, cracked product, comparatively free from uncracked oils and other undesirable products. In fact, it may be much more readily purified than the cracked oils heretofore produced by other commercial 105 processes. Provision is made for such a thorough reflux action as to practically preclude all uncracked vapors from entering the condensing coil *d*, thereby materially increasing the effectiveness of the process. 110

In practice, it is found that even when the oil is subjected to the highest temperatures required, the walls of the still remain relatively cool, and, accordingly, the danger of exploding the still is entirely avoided. 115 I am thus enabled to employ much higher temperatures, as well as much greater pressures, than could possibly be availed of in an externally heated still, and with practically no attendant danger. Accordingly, the efficiency of the process is very materially higher than those processes dependent on external heating. As a further result, I am able to successfully crack oils, such as kerosene, having a range of boiling 120 points above 130 degrees C. and below 260 degrees C. None of the processes in commercial use can be utilized for cracking kerosene successfully since their commercial operation is restricted to hydrocarbons hav- 125 130

ing boiling points upwards of 260 degrees C. This fact emphasizes the pronounced difference in applicant's process, and its inherent advantages over the processes now in use. Moreover, the durability of the still is greatly enhanced for the reasons adverted to.

Applicant has observed that, when cracking oils in externally heated stills, carbide 10 of iron is produced to a material extent, which carbide reacts on the oil, under the conditions of operation, to produce aromatic hydrocarbons, an undesirable result. This result is obviated by applicant's process.

15 It will be understood that while applicant's process has been described in its entirety, the invention is not limited to all the operations set forth, but is as broadly novel as is commensurate with the appended 20 claims.

Having thus fully described the invention, what I claim as new and desire to secure by Letters Patent is:

1. The process of converting heavy hydrocarbons into lighter hydrocarbons which 25 consists in heating a relatively large body of such heavy hydrocarbons to a suitable cracking temperature, but considerably below the incandescent temperature of carbon, by a plurality of electric resistors of massive construction submerged in the oil and while maintaining the oil at a minimum autogenous pressure of 75 pounds.

2. The process of converting heavy hydro-

carbons into lighter hydrocarbons which 35 consists in heating a relatively large body of such hydrocarbons to a temperature considerably below the incandescent temperature of carbon, in a still or receptacle of the general type used for cracking, by a plurality of electric resistors of massive construction submerged in the oil and while maintaining the pressure in the still in excess of 75 pounds.

3. The process of converting heavy hydrocarbons into lighter hydrocarbons which 45 consists in heating a relatively large body of such hydrocarbons to a temperature considerably below the incandescent temperature of carbon, in a still or receptacle of 50 the general type used for cracking, by a plurality of electric resistors of massive construction submerged in the oil, and sufficiently spaced from the walls of the still to preclude short circuiting and maintaining a 55 pressure in the still in excess of 100 pounds.

4. The process of converting heavy hydrocarbons into lighter hydrocarbons which comprises immersing in a relatively large body of said heavy hydrocarbons a plurality 60 of electrical resistors of massive construction and heating the said hydrocarbons by means of such resistors to the cracking temperature and pressure.

In testimony whereof I have signed the 65 foregoing specification.

OTTO P. AMEND.
